BRUSH

Mary J. McDonald, Arlington, Mass.

Application December 6, 1949, Serial No. 6,446

Term of patent 14 years

(Cl. D9—2)

To all whom it may concern:

Be it known that I, Mary J. McDonald, a citizen of the Dominion of Canada and a resident of Arlington, in the county of Middlesex and State of Massachusetts, have invented a new, original, and ornamental Design for a Brush, of which the following is a specification, reference being had to the accompanying drawings, forming part thereof.

I claim:

The ornamental design for a brush, as shown.
MARY J. McDONALD.
